(57) **CLAIM**

The ornamental design for a combined helmet eye shield and underlying visor, as shown and described.

DESCRIPTION

FIG. 1 is a perspective illustration, from the front and left side of a combined helmet eye shield and underlying visor showing our design, the visor being shown in the raised position;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom plan view thereof.

In each of FIGS. 1-6, the broken lines showing structure are for illustrative purposes only and form no part of the claimed design.
